UNITED STATES PATENT OFFICE.

LEOPOLD REBEL, OF PARIS, FRANCE, ASSIGNOR TO LA SOCIETE PARISIENNE
D'ESSENCES RARES & DE PARFUMS, OF PARIS, FRANCE.

DESIGN FOR A FLACON.

Application filed June 29, 1926. Serial No. 18,206. Term of patent 7 years.

To all whom it may concern:

Be it known that I, LEOPOLD REBEL, a citizen of the Republic of France, residing at Paris, France, have invented a new, original, and ornamental Design for Flacons, of which the following is a specification, reference being had to the accompanying drawing, forming a part thereof.

In the drawing,

I claim:

The ornamental design for a flacon substantially as shown.

LEOPOLD REBEL.
